WALLET CLIP

Louis L'Esperance, Washington, D. C., and
Eli Y. Keith, West Palm Beach, Fla.

Application August 20, 1948, Serial No. 45,276

2 Claims. (Cl. 150—47)

1

This invention relates to novel and useful improvements in means for holding articles in the pockets of wearing apparel, and more particularly relates to a device for retaining a foldable wallet or pocket book in the rear pocket of a man's trousers.

The primary object of this invention is to provide a sturdy and simple device which is adapted for detachable engagement with a wallet or pocket book and which functions to prevent accidental or unauthorized withdrawal of the wallet from the pockets of wearing apparel.

Another important object of this invention is to provide a wallet clip which can be conveniently and dependably employed with any type of foldable wallet, which will prevent a withdrawal of the wallet from a pocket by engaging the sides of the pocket, and which will lend itself to an inexpensive manufacture.

A meritorious feature of this invention resides in the simplicity of the device and in the manner in which it is detachably associated with a wallet.

These and ancillary objects and other meritorious features to become apparent upon a perusal of the following description are attained by this invention, preferred embodiments of which are set forth in the following specification and illustrated in the accompanying drawing, wherein:

Figure 1 is a view in perspective of a conventional foldable wallet or pocket book showing this invention in association therewith;

Figure 2 is a perspective view of one embodiment of this invention;

Figure 3 is a perspective view of a portion of a foldable wallet, depicting another embodiment of this invention in operative engagement in association therewith; and

Figure 4 is a plan view of the embodiment shown in Figure 3.

This invention, generally designated by the character reference 10, is designed and adapted for use with any type of foldable wallet or pocket book and functions to prevent an unauthorized withdrawal or removal of a wallet from pockets.

With respect to Figure 2 of the drawings, it is to be noted that the clip or wallet guard, constituting this invention 10, comprises a substantially rectangular open frame 12 having a pair of longitudinal parallel side bars 14 and 16. The longitudinally extending opposed bars 14 and 16 are joined at their opposite ends by transverse end bars 18 and 20.

The clip 10 is adapted to be inserted between the foldable ends 22 and 24 of a conventional

wallet or pocket book 26, adjacent the fold point 28 thereof. In this respect, suitable means is provided for detachably associating or attaching the clip to the wallet and comprises a tab or plate 30, which is inserted and received within a compartment or pocket 32 formed in one side of the wallet, as is customary.

In Figure 2 of the drawings, the tab 30 is illustrated in integral formation with the side bar 16. 10 The tab 30 extends inwardly from the side 16 adjacent to the side 14 and is disposed transversely between the sides in spaced placement from the ends 18 and 20. The forward or unattached portion of the tab is preferably formed with a curved or arcuate edge 34, the edge terminating in a plane below the common plane of the rectangular frame and the attached end of the tab.

The slight bend away from the plane of the frame given to the end of the tab allows the same to be easily and conveniently inserted within the compartment 32 of the wallet, as seen in Figure 1.

It can be appreciated that only one part is provided and that there are no movable parts. This enhances the structural, economical and utilitarian value of the device, since the clip may be easily stamped out of a semi-flexible material in operation and will be sturdy and dependable, obviating any possibility of inherent defects or subsequent damage or injury due to breakage or the like.

In use, the clip is attached to a wallet by inserting the tab within the compartment or pocket 32 so that the end bars 18 and 20 project evenly beyond the opposing longitudinal marginal edges of the section 22 of the wallet. The sections are then brought together so that the clip is sandwiched between the sections and the wallet 35 is inserted within a pocket, this pocket usually being the rear pocket in a man's trousers. The wallet is inserted by inserting one of the corners of the clip into the pocket first and then moving the wallet, so that the ends 18 and 20 of the clip 40 engage the opposite walls of the pocket. It can thus be seen that the end bars 18 and 20 and the corners formed thereby in association with the side bars will grip against and dig into the material of the pocket so as to prevent an unauthorized withdrawal of the wallet. An authorized withdrawal can be easily and conveniently effected by merely moving the wallet in the pocket so as to disengage the end bars from the walls of the 45 pocket.

Another embodiment of this invention is illus-

trated in Figures 3 and 4, the same serving the same function as the device in Figures 1 and 2 and retaining the same principle. However, the clip shown in Figures 3 and 4 is structurally different, though employing a similar structure for effecting the primary aim and purpose of this invention.

In this respect, the modified form of clip includes the same open rectangular frame or framework 12 but utilizes a different type of securing means in association with the wallet. The tab 30 in the clip 40 illustrated in Figures 3 and 4 is flexible and is employed in a different function, with the means for attaching the clip to the wallet comprising a flexible tab 42 which has one end 44 secured about the side wall 14 by means of permanent stitching 46. The tab 42 is thus slidably mounted for longitudinal movement on the side bar 14, so that the end bars 18 and 20 may be transversely adjusted with respect to the longitudinal marginal edges of the wallet section. The tab 42 is preferably formed of a width substantially equal to the width of conventional wallets but, of course, the dimensions of the tab would vary in conformity with the size of the wallet.

The tab 30 is bent at its free end downwardly of the frame so that it presses the side bar 14 away from the wallet when the clip is attached to the wallet. When a person desires to withdraw the clip, a pressure is applied to the side bar 14, forcing the same against the wallet.

While in the foregoing, preferred embodiments of this invention have been shown and described, the main features of this invention are the open rectangular frame which can be formed of wire or a like flexible material and the means provided for detachably associating the frame with a wallet so that the end bars of the frame will engage and grip in the material of a pocket and will prevent an unauthorized withdrawal of the clip from the pocket.

Therefore, certain changes could be carried out such as forming the open frame in the form of a square or multi-sided frame and employing integral or detachable wallet engaging means.

Having described the invention, what is claimed as new is:

1. In a wallet of the type including a pair of integrally formed hingedly connected sections at least one of which is provided with a compartment having an opening at the juncture of the sections, an attachment for the wallet to prevent unauthorized removal of the wallet from a user's pocket, said attachment comprising a flat, open, substantially rectangular frame member of a length greater than the width of the compartment and of a width less than the length of said compartment, and a flat tongue element integrally formed with one side edge of the frame member intermediate the ends of the frame member and extending toward the other side edge of the frame member, said tongue element having a free end provided with a convex edge received in the compartment through the opening thereof, said frame member overlying the compartment and extending transversely across and beyond said compartment.

2. As a new article of manufacture, a wallet clip comprising a substantially rectangular open frame having a pair of longitudinal parallel side bars and a pair of parallel end bars joining the side bars, and a plate integrally formed with one of said side bars intermediate the ends thereof and extending toward the other of said side bars, said plate having a free end provided with a convex edge facing said other side bar.
